UNITED STATES PATENT OFFICE.

THOMAS H. EUBANK, OF NEW BERN, NORTH CAROLINA.

STAMP OR CABINET CASE.

Application filed July 3, 1921. Serial No. 483,312.

To all whom it may concern:

Be it known that I, THOMAS H. EUBANK, a citizen of the United States, residing at New Bern, in the county of Craven and State of North Carolina, have invented a new and useful Stamp or Cabinet Case, of which the following is a specification.

The present invention relates to cabinets or cases especially designed for retaining 10 stamps or similar valuable articles.

The primary object of the invention is to provide a case of this character having a plurality of tiers of drawers, novel means being provided to lock the respective tiers 15 by a single locking door so that a cabinet may be used by several persons avoiding the necessity of providing a separate cabinet for each clerk.

A further object of the invention is to 20 provide a cabinet of this character which may be revolved on its stand to bring a particular tier of drawers to a position where the drawers are easily accessible.

With the foregoing and other objects in 25 view which will appear as the description proceeds, the invention resides in the combination and arrangement of parts and in the details of construction hereinafter described and claimed, it being understood 30 that changes in the precise embodiment of the invention herein disclosed, may be made within the scope of what is claimed, without departing from the spirit of the invention.

Referring to the drawings:—

35 Figure 1 is a side elevational view of a cabinet constructed in accordance with the present invention.

Figure 2 is a sectional view taken on line 2—2 of Figure 1.

40 Figure 3 is a plan view of the stand.

Figure 4 is a longitudinal sectional view of a cabinet on line 4—4 of Figure 1 showing a modified form of support.

45 Referring to the drawings in detail, the device includes a stand comprising a table 5 and leg members 6, the table being provided with casings 7 in which the rollers 8 operate, the casings being of depths to retain a quantity of oil to insure the lubrication 50 of the rollers so that the body portion of the cabinet may move freely thereover.

The body portion of the cabinet includes 55 a casing indicated at 9, which casing has a portion thereof at each side wall, cut away, the walls formed by the cut away portion being connected by means of the partition-

ing members 10 which provide supports for the sliding drawers 11 which are disposed one above the other.

Hinged closures 12 are connected to the 60 casing and are designed to close the cut out portions and contact with the drawers 11, to lock the closure and eliminate any possibility of the drawers being opened by unauthorized persons, it being understood that 65 a suitable lock indicated at 14 is carried by each closure. The doors are provided with handles 13 whereby the same may be easily moved into and out of the cabinet proper.

A supporting post 15 is secured to the 70 stand, the same having connection with the table 5 thereof, the supporting post 15 being shown as extending through the tubular bearing member 16 that forms a part of the casing, the partitioning members 17 being 75 shown as having their inner ends secured to the tubular bearing as at 18 to provide compartments to receive the drawers. At the upper end of the supporting post are the nuts 19 that secure the casing to the post to 80 prevent displacement of the casing with respect to the stand.

This post 15 is provided with a cone-shaped bearing at one end thereof, the bearing being indicated by the reference character 15'. Formed longitudinally of the post 15 is a groove 16' which is in communication with the opening 23 formed in one of the nuts 19, so that lubricants directed to the opening 23 will pass along the post 15 90 and run over the bearing 15' to lubricate the roller bearings 20 which move thereover.

A ball cage 21 is secured to the lower wall of the casing as by means of the screws 22 and support the ball bearings 20 in proper 95 position on the cone-shaped bearing 15'.

From the foregoing it will be seen that a single cabinet may be provided with a number of tiers of drawers, each tier being locked by a closure such as described, it being understood that in the use of the device, a clerk will have the responsibility of guarding and accounting for the articles contained in a particular tier of drawers, and to this end it is contemplated that the locks of the 100 closures may be varied so that the key which opens one lock will not open the closure associated with another tier of drawers.

It will thus be seen that when clerks 110 are relieved, the clerks assuming duty will revolve the cabinet until the tier of drawers over which he has authority is moved to an

accessible position, the clerk who has been relieved locking his tier of drawers, thereby eliminating the necessity of taking inventory when another corps of clerks goes on duty.

It may be found desirable to supply a track section to the lower portion of the case, to facilitate the operation of the case.

Having thus described the invention, what is claimed as new is:—

A revolving cabinet having a plurality of sides, a plurality of drawers insertable in each side, said drawers having handles, and a closure for each side hinged to the cabinet portion and adapted to swing in front of

the drawers and be locked in such position to hold the drawers against removal, said closures having elongated rectangular cut out portions providing a clearance to permit the handle to extend therethrough, whereby an operator may grasp the same in revolving the cabinet. 20

In testimony that I claim the foregoing as my own, I have hereto affixed my signature in the presence of two witnesses.

THOMAS H. EUBANK.
